UNITED STATES PATENT OFFICE

2,580,523

CIGARETTE HOLDER

Albert J. Crone, Cincinnati, Ohio

Application July 20, 1945, Serial No. 606,119

1 Claim. (Cl. 131—181)

1

My invention relates to cigarette holders and has for an object to provide in such a device means to minimize the danger of fires being started by cigarettes.

Another object of this invention is to provide a cigarette holder so formed that the entire cigarette may be consumed.

A further object of the invention is to provide in a cigarette holder a heat dissipating device.

A still further object of this invention is to provide a stem within which a cigarette may be held and means for automatically moving the cigarette so that the lighted end is visible and exposed to the atmosphere.

Other features and advantages will become more readily apparent from the following description and the accompanying illustrative drawings in which:

Figure 1 is an elevational view of my cigarette holder.

Figure 2 is a longitudinal, sectional view of a stem of the device.

Figure 3 is a longitudinal, sectional view of Figure 1, partly broken away.

Figure 4 is a similar view showing a spring expanded.

Figure 5 is a broken away end of a mouth-piece, looking in the direction of line 5—5 of Fig. 1.

Figure 6 is an end view of Figure 1, and

Figure 7 is a section on line 7—7 of Figure 1.

My invention 10, as illustrated in the accompanying drawings, includes a stem 11 and a mouth-piece 12. The stem 11, from end 13 to end 14, is cylindrical internally and of a length to receive a major portion of a cigarette 15, which is freely slidable within said stem 11. The end 13 of stem 11 is chamfered out as indicated at 16, in order that the cigarette may be easily inserted. The end 14 of stem 11 is screw-threaded to receive the threaded end 17 of the mouthpiece 12, the latter being provided with an outwardly grooved projection 18 at its inner end and around which is secured the inner end 19 of a coil spring 20. To the end 21 of the spring is secured a pusher cup 22, by means of an outwardly grooved stem 23 of the pusher cup and around which stem the terminal of the spring is secured. The cup 22 frictionally holds the end 24 of the cigarette in order that it will still be held in horizontal position after it has been pushed beyond the said end 13.

Threadedly mounted upon the outer portion 25 of the stem 11, is a member 26, including a ring 27, secured to the end 13 of said stem 11.

2

From the ring 27 extend arms 28, 29, to the outer ends 30 of which is secured a ring 31. In the embodiment of the invention illustrated in the drawing, the stem 11 has an externally threaded portion and the ring 27 comprises an intermediate portion of the member 26, this intermediate portion being internally threaded and engaged on said externally threaded portion, while the arms 28 and 29 are integral forwardly extending portions of member 26 and terminate in the ring 31. Fixed to the arms 28, 29, and inwardly of ring 31, is a pair of fine tungsten steel wires 32 and 33, against which the lighted end 34 of the cigarette 15 is forced through the action of the spring 20. The member 26, with the arms 28, 29, and ring 31, constitute a cage, to permit free passage of air and convenient lighting of the cigarette. The longitudinal openings 35 in member 26 permit access of air to the body portion 25 of stem 11, to prevent heating thereof as a result of its proximity to the lighted end of the cigarette. Beyond the edge 36 of the said member 26, the stem 11 uniformly tapers toward the head 37 of the mouthpiece as clearly indicated in Figure 1 of the drawings. A clip 38, is provided on the member 26, for securing the device to a pocket of the user.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

The spring is removable with the mouth-piece. Due to the construction of my cigarette holder as above outlined, it will be obvious that the lighted end of the cigarette is held in such a manner as to keep it out of contact with anything externally of its cage and if a cigarette holder of the character described herein and with a lighted cigarette therein were mislaid in a bed the danger of fire would be lessened. Furthermore, the entire cigarette can be consumed, no portion being wasted, so in the aggregate it will be a money saver. It is obvious that larger sizes may be made for cigars.

Having now described my invention that which I claim as new and desire to procure by Letters Patent is:

A cigarette holder comprising a mouth piece, a tubular stem threadably secured to said mouth

piece at one end and flared to facilitate the insertion of a cigarette thereinto at the other end, a cup adapted to slide within said stem and to receive and to retain one end of a cigarette, a helical spring compressed between said cup and said mouth piece to urge said cigarette out of said stem, said other end of the stem having an externally threaded portion, a member including an aperture protective grill surrounding the said stem adjacent said flared end thereof, said member having an intermediate portion thereof comprising a ring internally threaded and engaging said externally threaded portion of the stem, arms integral with and extending forwardly from said ring, another ring secured to the forward ends of the arms, and heat-resistant cross wires secured to and between said arms to abut a lighted end of a cigarette, whereby said cigarette is supported with the lighted end thereof visible and substantially open to the atmosphere. 20
